UNITED STATES PATENT OFFICE.

KARL BARTH, OF ESSEN-ON-THE-RUHR, GERMANY, ASSIGNOR TO FRIED. KRUPP AKTIENGESELLSCHAFT, OF ESSEN-ON-THE-RUHR, GERMANY.

SELF-UNLOADING RECEPTACLE.

1,140,240.

Specification of Letters Patent. Patented May 18, 1915.

Application filed June 9, 1914. Serial No. 844,065.

To all whom it may concern:

Be it known that I, KARL BARTH, residing at Essen-on-the-Ruhr, Germany, a citizen of the German Empire, have invented 5 a certain new and useful Improvement in Self-Unloading Receptacles, of which the following is a specification.

The present invention relates to self-unloading receptacles of the class shown and 10 described in the co-pending application, Serial No. 796272, filed October 20, 1913.

The object of this invention is to provide 15 a very simple construction to permit unloading in either one or the other side of the receptacle.

In the accompanying drawings is illustrated one embodiment of the present invention representing a self-unloading car, and Figure 1 shows a transverse section of 20 the car in loading position; Fig. 2, a similar section of the car in intermediate position during the unloading; Fig. 3, a similar section of the car after unloading to the right side and, Fig. 4, a section similar 25 to that shown in Fig. 1 of a car after unloading to the left side.

On the bottom frame A of the car are secured parallel to each other the two end walls A¹. A pedestal bearing A² is moreover securely mounted on the under frame A at each of its front and rear ends. Two double armed levers C situated symmetrically on each side of the middle longitudinal plane of the car are by means of journals 30 c¹ connected to each of the pedestal bearings A² in which bearings rests a trough-running longitudinal shaft B provided with two securely fastened sectors b¹. These levers C rest with each of their inner ends and by 35 the intermediary of rollers c², on the sectors b¹ respectively, when the car is in its loading position, see Fig. 1. Cup-shaped bearings c⁴ are provided between the journals c¹ and the rollers c² on the levers C. The outwardly directed arms c³ of the levers C have been so constructed, that its center of 40 gravity when they rest upon the sectors b¹ is situated perpendicularly beneath the axes of the journals c¹. In the cup-shaped bearings c⁴, the bottom D is supported by means 45 of trunnions d¹ when the car is in loading position, see Fig. 1, these trunnions being secured on reinforced suspension plates d² of the bottom D. In order to prevent the 50 bottom from tilting around the axes of the

trunnions d¹, situated on the one or the other side of the car, when the latter is in loading position that is when all the levers C rest upon the sectors b¹; still other trunnions d³ have been provided on the suspension plates d² above the trunnions d¹, these trunnions d³ resting against projections a³ of the pedestal bearings A². These projections are of such a shape that they only will prevent a tilting movement of the bottom when all of the levers C rest upon the sectors b¹ as already described; but that they permit such a tilting movement when the levers on one side of the car have lost their support. 50

In each pedestal bearing A² are moreover provided recesses a⁴ into which the trunnions d¹ may fall on the unloading movement. Lastly other recesses a⁵ are also provided on each pedestal bearing A² for the trunnions d³. These recesses a⁵ are situated so that the trunnions d³ are only at a short distance from them when the trunnions d¹, situated on the same side, have fallen into their recesses a⁴, while the trunnions d¹, situated on the opposite side, rest 65 in the bearings c⁴, see Fig. 2. Blocks a⁶ are secured on the underframe A for supporting the bottom in the unloading position. 70

In the loading position of the car, the side walls F which are provided with handles f¹, are supported at their upper ends on journals f² in bearings a⁷ which are open at the top and provided on the sides of the end walls A¹; and at their lower end by means of inclined angles f³ on rollers d⁴ 75 which are carried in bearings on extensions d⁵ of the bottom D. The journals f² are guided by means of links G which are connected with the end walls A¹. 80

If the car is to be unloaded toward one side, say for instance to the right, the shaft B has to be turned in the direction of the arrow x, see Fig. 1. The sectors b¹ will then get out of the path of the levers C situated to the right, which then lose their support 95 and swing away in the direction of the arrow y, actuated by the weight of the bottom and the load, transmitted through the trunnions d¹. The trunnions d¹ situated to the left remain in their bearings c⁴, see Fig. 100 2, so that the bottom D, during its subsequent tilting movement, turns around the axes of these trunnions, and that the rollers d⁴ situated to the right, leave the bearings formed by the inclined angles f³ of the right 105 110

hand side wall F. The trunnions d^1 situated to the right now slide out of their bearings c^4 and fall into the recesses a^4 , see Fig. 2. Simultaneously the trunnions d^3 situated to the left get out of reach of the corresponding projections a^3 , and the trunnions d^3 situated to the right arrive into the position adjacent to the corresponding recesses a^5 . The left hand side wall F will 10 be raised by the bottom, the journals f^2 leaving the bearings a^7 , while the right hand side wall remains suspended with its journals f^2 in the bearings a^7 . As soon as the right hand trunnions d^1 have fallen 15 into the recesses a^4 , the bottom D tilts still further, actuated by the load, and it now turns around the axes of the trunnions d^1 which have fallen into the recesses a^4 . Simultaneously the left hand trunnions d^1 raise themselves from the bearings c^4 , see 20 Fig. 3. In this manner the bottom finally arrives in the unloading position, see Fig. 3, wherein the trunnions d^3 are resting in the recesses a^5 and the bottom D simultaneously 25 is supported by the blocks a^6 .

After finishing the unloading, the raised side wall F is drawn downward by means of the handles f^1 until the journals f^2 have entered the bearings a^7 . At the same time 30 the bottom D swings out of its unloading position, see Fig. 3, back into the position shown in Fig. 1, while it turns first around the axes of the right hand trunnions d^1 and thereupon, after the left hand trunnions d^1 35 have again entered the bearings c^4 , around the axes of the latter. At the same time the right hand levers C return automatically into their position shown in Fig. 1 as a consequence of the above described construction 40 of the lever arms c^3 . The sectors b^1 have now to be returned to their middle position. The bottom is then secure. If the car is to be unloaded toward the other side, that is toward the left, the sectors b^1 have to be 45 turned into the opposite direction to the arrow x . The operation, compare Fig. 4, corresponds completely to the one described and needs therefore not be further entered upon.

50 I claim:

1. In a self-unloading receptacle constructed to discharge selectively in two opposite directions; a main frame, an oscillating bottom, bearings for the bottom mounted on said frame, said bearing members being movable in an approximately vertical direction and arranged on both sides of the middle line of the receptacle; movable side walls, interlocking connections between the bottom and the side walls, said connections during the tilting of the bottom for unloading, being automatically broken between said bottom and that side wall which at the time is situated on the discharging side.

55 2. In a self-unloading receptacle con-

structed to discharge selectively in two opposite directions; a main frame, an oscillating bottom, bearings for the bottom mounted on said frame, said bearing members being movable in an approximately vertical direction and arranged symmetrically on both sides of the middle line of the receptacle; movable side walls, interlocking connections between the bottom and the side walls, said connections during the tilting of the bottom for unloading, being automatically broken between said bottom and that side wall which at the time, is situated on the discharging side; said movable bearing members comprising a pair of opposing levers, the axes of revolution of which run in the longitudinal direction of the receptacle, a supporting member, situated centrally in said frame; said member simultaneously supporting the free ends of said levers when the receptacle is in loading position and said supporting member, on being displaced in the direction of one of said levers, disengaging the other, during the opening operation.

60 3. In a self-unloading receptacle constructed to discharge selectively in two opposite directions; a main frame, an oscillating bottom, bearings for the bottom mounted on said frame, said bearing members being movable in an approximately vertical direction and arranged symmetrically on both sides of the middle line of the receptacle; movable side walls, interlocking connections between the bottom and the side walls, said connections during the tilting of the bottom for unloading, being automatically broken between said bottom and that side wall which at the time is situated on the discharging side; said movable bearing members comprising a pair of opposing levers, the axes of revolution of which run in the longitudinal direction of the receptacle, a supporting member situated centrally in said frame; said member simultaneously supporting the free ends of said levers when the receptacle is in loading position and said supporting member, on being displaced in the direction of one of said levers, disengaging the other, during the opening operation, 65 said levers being provided with cup-shaped bearings and the bottom with corresponding journals, said main frame being provided with recesses adapted to receive the journals of the bottom, the bearing, on the lever, which is at the time disengaged, permitting the corresponding journal to leave it and to enter the corresponding recess provided in said main frame.

65 4. In a self-unloading receptacle constructed to discharge selectively in two opposite directions; a main frame, an oscillating bottom, bearings for the bottom mounted on said frame, said bearing members being movable in an approximately vertical 70 direction and arranged on both sides of the middle line of the receptacle; movable side walls, interlocking connections between the bottom and the side walls, said connections during the tilting of the bottom for unloading, being automatically broken between said bottom and that side wall which at the time, is situated on the discharging side; said movable bearing members comprising a pair of opposing levers, the axes of revolution of which run in the longitudinal direction of the receptacle, a supporting member, situated centrally in said frame; said member simultaneously supporting the free ends of said levers when the receptacle is in loading position and said supporting member, on being displaced in the direction of one of said levers, disengaging the other, during the opening operation.
